(57) **CLAIM**

The ornamental design for a tampon applicator, as shown and described.

DESCRIPTION

FIG. 1 is a front, top perspective view of a tampon applicator showing our new design;

FIG. 2 is a rear, bottom perspective view thereof;

FIG. 3 is a top plan view thereof;

FIG. 4 is a bottom plan view thereof;

FIG. 5 is a left side elevation view thereof;

FIG. 6 is a right side elevation view thereof;

FIG. 7 is a rear elevation view thereof; and,

FIG. 8 is a front elevation view thereof.

The front face of the tampon applicator is flat/planar, and the rear face of the tampon applicator defines a concave recess.

The broken lines are for the purpose of illustrating portions of the article that form no part of the claim.
